UNITED STATES PATENT OFFICE

2,577,008

TOURNIQUET CLAMP

Oscar L. Engstrom, New York, N. Y.

Application June 18, 1949, Serial No. 100,009

1 Claim. (Cl. 128—327)

1

This invention relates to surgical instruments, and more particularly to a tourniquet clamp or hemostatic ligators of the type having a pair of clamping members which are pivoted together in a scissors arrangement, and which are provided with a ratchet device for holding said members in any desired adjusted position.

One object of this invention is to provide a tourniquet clamp of the above nature in which the ratchet device is disposed closely adjacent the pivot so as to avoid obstructing the use of the clamp.

Another object is to provide a tourniquet clamp of the above nature wherein the ratchet device is secured to one clamping member by means which is so arranged as to avoid weakening the clamping members.

Another object is to provide a tourniquet clamp of the above nature in which the ratchet device will be effective throughout a wide range of movement of the clamping members.

A further object is to provide a tourniquet clamp of the above nature which will be simple in construction, inexpensive to manufacture, easy to use and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 is a side view of the improved tourniquet clamp.

Fig. 2 is a fragmentary side view of a portion of the clamp, shown on a larger scale.

Fig. 3 is a perspective view of the clamp.

Referring now to the drawings, in which like reference numerals denote corresponding parts throughout the several views, the numerals 10 and 11 indicate a pair of elongated clamping members which are pivotally secured together in a scissors arrangement by means of a screw 12, and which comprises handle portions 13, 14 and curved jaw portions 15, 16 respectively.

It will be understood that the jaw portions 15, 16 are disposed in slightly offset relationship so that they may overlap and thus be brought close together for clamping small objects.

The clamping members 10, 11 have intermediate crossing portions 17, 18 which are of a reduced thickness so as to embrace the sides of a flat steel ratchet sector 19, located in the crossing portion 17 of the member 10 and preferably formed integral therewith.

2

The sector 19 is provided with a series of ratchet teeth 20 disposed concentrically with respect to the pivot screw 12 and are adapted to be engaged by a nose 21 of a detent lever 22.

The detent lever 22 is pivotally mounted upon a lug 23 integrally formed on the outer side of the handle portion 14 adjacent the sector 19, and is engaged by a leaf spring 24 which urges the nose 21 into engagement with the ratchet teeth 20. The spring 24 is attached to the handle portion 14 of the member 11 by any suitable means, such as a rivet 25.

In order to impart an automatic opening movement to the clamping members 10, 11 when the detent lever 22 is disengaged from the sector 19, provision is made of an elongated leaf spring 26 which is attached to the inner surface of the handle portion 13 by means of a rivet 27, and which bears against the inner surface of the handle portion 14 in the region of the lug 23.

Operation

In use, the curved jaw portions 15, 16 will first be disposed so as to embrace the object to be clamped and the handle portions 13, 14, will then be pressed toward each other, this operation simultaneously causing the jaw portions 15, 16 to engage the object, and causing the nose 21 of the lever 22 to ride in a clockwise direction over the ratchet teeth 20, as viewed in the drawing. The handle portions 13, 14 will then be released by the operator, whereupon the leaf spring 24 will maintain the nose 21 in engagement with the teeth 20, thereby preventing separating movement of the jaw portions 15, 16.

When it is desired to release the clamping members 10, 11, it will merely be necessary to press the detent lever 22, thus disengaging the nose 21 from the teeth 20, and permitting the jaw portions 15, 16 to separate.

This separating movement will, of course, be facilitated by the action of the elongated leaf spring 26, which will cause the clamp to open automatically and permit it to be removed with a minimum of interference with the object clamped, and without requiring the operator to exert any positive opening force upon the jaws. This feature will also be of assistance in applying the clamp upon the object since a mere pressure of the thumb upon the detent lever 22 will result in separation of the jaw portions 15, 16.

While there has been disclosed in this specification one form in which the invention may be embodied, it is to be understood that this form is shown for the purpose of illustration only, and

that the invention is not to be limited to the specific disclosure, but may be modified and embodied in various other forms without departing from its spirit. In short the invention includes all modifications and embodiments coming within the scope of the following claim.

Having thus fully described the invention, what is claimed as new, and for which it is desired to secure Letters Patent is:

In a tourniquet clamp, a pair of clamping members pivoted together in crossing relationship, a toothed ratchet sector on one of said members and embracing the pivot, a detent lever mounted upon the other of said members and adapted to engage said sector, and a spring urging said detent lever into engagement with said sector.

OSCAR L. ENGSTROM.
